UNITED STATES PATENT OFFICE.

ARTHUR P. CONANT, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE BEZEL.

Application filed February 22, 1929. Serial No. 30,171. Term of patent 14 years.

To all whom it may concern:

Be it known that I, ARTHUR P. CONANT, a citizen of the United States, residing at Fort Thomas, in the county of Campbell and State of Kentucky, have invented a new, original, and ornamental Design for Watchcase Bezels, of which the following is a specification, reference being had to the accompanying drawing, forming part thereof.

Fig. 1 is a plan view of a watchcase bezel showing my new design;

Fig. 2 is a perspective view thereof; and

Fig. 3 is a central longitudinal view of Fig. 2.

I claim:

The ornamental design for a watchcase bezel, substantially as shown.

ARTHUR P. CONANT.
